UNITED STATES PATENT OFFICE

DAVID E. JUSTUS, OF KANSAS CITY, MISSOURI

TOILET SEAT

Application filed July 13, 1928. Serial No. 292,449.

My invention relates to toilet seats, and more particularly to secondary toilet seats and lids therefor adapted for use by small children, the principal objects of the invention being to provide a secondary seat in a toilet seat cover and to hinge a secondary seat lid to the cover so that the lid and hinge members will be spaced from the secondary seat in open position of the lid and will lie flush with the cover in closed position, whereby the upper surface of the cover will be smooth when the lid is closed, and comfort, convenience and safety of both adult and child users will be promoted, and hazard of damage to the cover, lid and other members of the toilet fixture will be avoided.

In accomplishing these and other objects of my invention, I have provided improved details of structure, the preferred forms of which are illustrated in the accompanying drawings, wherein:

Fig. 1 is a perspective view of a position of a toilet fixture embodying my invention, illustrating a secondary seat lid in closed position.

Fig. 2 is a similar view illustrating the lid in open position and showing the hinge.

Fig. 3 is a longitudinal central sectional view of the toilet seat, cover and secondary seat lid illustrating the means for latching the lid to the cover in closed position.

Fig. 4 is an enlarged detail perspective view of the hinge.

Referring in detail to the drawings:

35 1 designates a toilet seat supported by a toilet fixture 2 and having an opening 3 closed by a cover 4 adapted to rest on the seat and pivotally connected with the fixture by hinges 5.

40 The cover is provided with an opening 6 preferably by cutting a lid portion 7 therefrom and preserving said portion intact to comprise the lid or cover for the opening 6. The lid portion is cut out in a manner to form 45 a tapering ledge or bevel edge 8 for the opening 6 and a peripheral bevel flange 9 on the lid whereby the lid may fit neatly in the opening and be supported from the cover.

The lid is pivotally connected with the cover by a hinge generally designated 10 and

comprising a cover hinge member 11 mortised in the cover and a lid hinge member 12 mortised in the lid. The cover hinge member 11 consists preferably of a strap-like piece of metal comprising a body portion 13 adapted to lie in a transverse recess 14 formed in the cover adjacent the ledge 8, and angularly extending arms 15 comprising leaves on the outer ends of the body portion. These arms are received in parallel vertical slots 16 in the cover, extending through the ledge 8 and beyond the recess 14, the body portion being secured to the cover by a screw 17, the head of which is flush with the upper surface of the body portion. The slots form a hinge-supporting bracket or lug 18 extending toward the opening.

The member 11 overlies the lug and further comprises flanges 19 backbent over the arms 15 and spaced therefrom to form sockets 20 to receive lid hinge members presently described, and terminal ears 21 bent into parallelism with the body portion 13 and seated in recesses 22 in the cover aligned with the transverse recess 14 in the lug 18. Screws 23 secure the ears to the cover for reinforcing the lug.

The lid hinge member 12 comprises a plate 24 adapted to fit in a recess 25 in the lid inwardly from the flange 9, and plate-like arms 26 integral with the plate 24 extending at right angles to the plane of the plate 24 and in parallel lid slots 27, and having parallel side edges 28 and 29 extending angularly to the side edges of the plate. The outer ends 30 of the arms 26 extend angularly to the arms and are received between the portions 15 and 19 of the cover hinge member and are pivotally connected therewith by pins 31. The outer ends of the arms are thus mounted in the sockets 20 which form tracks or guides for their movement, and the lid hinge member is supported from the lug and from the adjacent portions of the cover. The hinge member 12 is secured to the lid by 90 countersunk screws 32.

Embedded in the cover 4 is a socket member 33 comprising a screw having a concave head 34 countersunk in a notch 35 in the ledge 8, and a spring-pressed plunger 36 slidably in 100

a tubular guide 37 mounted in a recess 38 of the lid is adapted to engage the head 34 to latch the lid to the cover in closed position. The plunger is limited in outward movement by engagement of a flange 39 on the inner end of its stem 40 with a shoulder 41 of the tubular guide. A spring 42 bears against said shoulder and the plunger for yieldingly latching the plunger with the screw 33.

10 It is apparent that with a secondary toilet seat and lid constructed and installed as described, the lid will fit snugly in the opening of the cover, and will be supported by the bevel ledge, the incidental steps such as painting and varnishing, supplying the place of material removed by cutting out of the lid member so that the lid will lie flush with the surface of the cover.

15 The plate-like arms of the lid hinge being pivoted at points spaced from the opening will swing the lid rearwardly from the opening when the lid is lifted, and the spaced slots in which the lid hinge arms move provide for sinking the hinges in the cover in closed position of the lid. The socket-forming portions of the cover hinge member which are sunk in the cover and connected respectively with the lug and the cover, serve to support the arms of the lid hinge member and confer 20 rigidity and durability.

25 The lid is easily operable both for opening and closing, proper seating of the lid on the cover is assured by the spaced plate-like lid hinge members, and no parts of the device 30 are exposed in such a position as to cause damage while being used.

35 What I claim and desire to secure by Letters Patent is:

1. In a toilet device including a seat and a 40 cover having a tapered opening, a lid having bevel edges for seating in said opening for support from the cover, and a hinge pivotally connecting the lid with the cover comprising a cover member including a body portion mortised in the cover and in integral arm extending from said body portion and secured to the cover, a lid member including a body portion mortised in the lid and an integral arm extending angularly from said body portion, 45 and means pivotally supporting the lid arm from the arm of the cover member.

2. In a toilet device of the character described including a seat, a cover comprising a body having a seat opening, a taper ledge 55 surrounding said opening, and parallel vertical slots extending through the ledge into the body, a lid comprising a body having a peripheral flange tapered to mate with said ledge for support of the lid from the cover 60 and parallel slots extending through said flange into the lid body, and a hinge including a cover member comprising a body secured to the cover and leaves received by said cover slots, and a lid member comprising a body 65 secured to the lid and arms extending in said

lid slots and pivotally supported by said leaves.

3. In a toilet device of the character described including a seat, a cover having an opening and parallel vertical slots forming a lug extending toward said opening, a lid, means for supporting the lid from the cover to close said opening, and a hinge including a cover member secured to said lug and having integral leaves extending in said slots and a member secured to the lid and having angularly extending arms pivotally connected to said cover member leaves.

4. In a toilet device of the character described including a seat, a cover having an opening and a lug extending toward said opening, a lid, means for supporting the lid from the cover to close said opening, a hinge including a cover member overlying said lug and having angularly extending leaves bent back to form sockets, and a member secured to the lid and having angularly extending arms movable in said sockets and pivotally connected to said cover member, and means for frictionally latching the lid to the cover.

5. In a device of the character described, a support having an opening, a cover for the opening provided with a secondary opening and having parallel slots communicating with the opening, a lid adapted to fill said secondary opening and having parallel slots adapted for alignment with the cover slots, and a hinge for pivotally connecting the lid with the cover comprising a strap-like member including a body mortised in the cover, socket portions extending in the cover slots and spaced from the opening, and ears secured to the cover, and a lid hinge member including a body secured to the lid, plate-like leaves extending angularly from the body in said lid slots, and having portions pivotally connected with said socket portions of the strap-like member, said leaves being movable into said cover slots for seating the lid in the secondary opening.

In testimony whereof I affix my signature.

DAVID E. JUSTUS.
